ULTRA HIGH FREQUENCY SWITCHING DEVICE

George E. Carter, Jr., Danvers, Mass., assignor to Bomac Laboratories Inc., Beverly, Mass., a corporation of Massachusetts

Application June 13, 1952, Serial No. 293,247

1 Claim. (Cl. 315—234)

This invention relates to ultra high frequency gaseous discharge switching devices, commonly referred to as transmit-receive TR tubes and more particularly to auxiliary means to aid in deionization of the resonant gap after the gaseous discharge.

Such devices are employed in radar systems to decouple the receiver during transmission of the high power pulse and, thereby protect the sensitive crystals from deterioration or "burn-out." In general, TR tubes comprise an evacuated resonant cavity, spaced electrodes forming a discharge gap and a gas fill under reduced pressure. When the transmitter is on, ionization of the medium in the resonant cavity causes a short circuit at the gap and because of the circuit arrangement of the TR tube, essentially all of the transmitted pulse is directed to the antenna.

The position of the TR tube in the system also permits the reflected returning signals received by the antenna to be transmitted to the receiver. The returning signals, however, are at too low a power level to cause ionization of the gas fill. In passing through the TR tube these weak signals will be attenuated in proportion to the ionization remaining after the previous high power transmitted pulse. It is, therefore, necessary that the gap be deionized as rapidly as possible after transmission.

Recovery time measured in microseconds is the term employed in the art to express the time interval when deionization occurs. Clearer definition and shorter minimum range in the operation of the radar system will result from a reduction in recovery time.

Since it is the electrons in the ionized gap that cause most of the attenuation of the reflected signals, their rapid removal is essential to obtain faster recovery times. It has been noted in the prior art, that a positive potential when applied to an auxiliary electrode extending into a resonant cavity will aid in the reduction of recovery time. Such positively biased auxiliary electrodes, however, have always been operated at a potential sufficiently high to cause a self-sustained direct current discharge, thereby necessitating the use of a high ballasting resistance in series with the direct current voltage supply and electrode so as to limit the current through the electrode to a safe value.

According to the teachings of the present invention, a positive potential below that necessary to cause a self-sustained direct current discharge is applied to an auxiliary electrode. If the impedance of the direct current voltage source is low to the transient current that occurs during the recovery period, a greatly reduced recovery time will be attained. A direct current voltage source, such as a battery having an inherent low impedance may be employed, or if the source has appreciable impedance to high frequency transients, a small condenser between the electrode and ground may be used to bypass the voltage supply.

It is an object of this invention to provide an ultra high frequency gaseous discharge switching device having rapid recovery time characteristics.

It is another object of the invention to provide a rapid

2

recovery time transmit-receive TR tube with a positive biased auxiliary electrode.

The foregoing and other objects and advantages of this invention will be apparent from the following detailed description taken in conjunction with the accompanying drawings, in which:

Figure 1 is a longitudinal cross section of the illustrative embodiment of the invention.

Figure 2 is a schematic diagram of the external circuit of the auxiliary electrode.

Figure 3 is a schematic diagram of another external circuit of the auxiliary electrode.

The selected illustrative device, as shown in Figure 1, comprises a circular metallic body member 1, defining an evacuated resonant chamber 2.

Within said chamber a pair of cones 3 and 4, slightly truncated and axially disposed from one another, are spaced a predetermined distance apart to form a discharge gap 5. Cone 3 is axially adjustable by means of screw 6 which is in threaded engagement with plug 7 and communicates with flexible diaphragm 8. Cone 4 is hollow to receive one end of an auxiliary electrode. Electrode 9, a component of the circuit of this invention, is positioned a short distance from the tip of cone 4 and communicates with the discharge gap by means of aperture 10 in the apex of the cone. The other end of electrode 9 extends through a glass reservoir 11 and is positioned in the center of cone 4 by means of a glass to metal seal as at 12. A top cap 13 is provided at the end of the electrode for connection with the external circuit.

In the illustrative embodiment of this invention, the tip of auxiliary electrode 9 is inserted to within approximately .015" of the tip of cone 4. As shown in Figure 2, the positive terminal of a direct current low impedance voltage source 14, desirably a battery is connected to the auxiliary electrode as shown at 15 with ground at 16. With a potential of approximately 150 volts or less applied, residual electrons present in the gap after a discharge will be effectively swept out of the gap toward this positively biased electrode.

Further, in the practice of this invention, it is important that the potential applied be below that necessary to cause a sustained direct current discharge of the gas fill employed. With a fill containing approximately 50 percent argon and 50 percent water vapor under a reduced pressure of 12 millimeters of mercury, absolute pressure, a direct current low impedance voltage source of approximately 150 volts or less will produce the fastest recovery time.

If a high impedance voltage source is employed as represented at 17 in Figure 3, it will be necessary to provide a condenser as at 18 of a value low enough to assure a low impedance to high frequency transients. This condenser will bypass the voltage supply thereby permitting the residual electrons to be drawn away from the gap to ground 16. Resultant recovery times measured with either circuit will be in the order of less than one microsecond.

While I have shown and described an illustrative embodiment of my invention, further variations and modifications will occur to those skilled in the art. It is, therefore, my intention to cover, in the appended claims, all such variations and modifications as fall within the true spirit and scope of this invention.

I claim:

In combination with a transmit-receive gaseous discharge switching tube having a gas-filled envelope, discharge gap electrode structure within said envelope and an auxiliary electrode extending into said envelope, means for providing said tube with rapid recovery time characteristics of one microsecond or less comprising a direct current voltage source electrically connected to said auxil-

iary electrode to provide a positive bias thereon, said voltage source having a potential below that necessary to maintain a direct current-self-sustaining glow discharge in the region adjacent the inner tip of said auxiliary electrode and a condenser connected between said auxiliary electrode and ground.
